UNITED STATES PATENT OFFICE.

OLAF E. GISET, OF NEW YORK, N. Y., ASSIGNOR TO A. WITTNauer CO., OF NEW YORK, N. Y.

STRIKING ATTACHMENT FOR TIMEPIECES.

1,160,065.

Specification of Letters Patent.

Patented Nov. 9, 1915.

Application filed July 18, 1913. Serial No. 779,687.

To all whom it may concern:

Be it known that I, OLAF E. GISET, a citizen of the United States, and a resident of the city of New York, borough of Brooklyn, in the county of Kings and State of New York, have invented a new and Improved Striking Attachment for Timepieces, of which the following is a full, clear, and exact description.

10 The object of the invention is to provide a new and improved striking attachment for watches and other timepieces, and arranged to strike the hours and half hours and to be driven from the main spring of

15 the timepiece.

In order to accomplish the desired result use is made of an auxiliary motor spring, wound up from the main watch spring when the latter is running down, striking devices 20 controlled by said auxiliary motor spring, an hour snail on the hour hand arbor of the timepiece, a spring-pressed main lever adapted to engage the said snail, and periodically actuated locking and releasing devices for the 25 said auxiliary motor spring and governed by the said main lever.

A practical embodiment of the invention is represented in the accompanying drawings forming a part of this specification, in 20 which similar characters of reference indicate corresponding parts in all the views.

Figure 1 is an enlarged face view of a watch provided with the striking attachment, parts of the cover, dial and hour hand being shown broken out; Fig. 2 is a similar view of the attachment, the cover, dial and hands of the watch being removed; Fig. 3 is a similar view of the driving gear for the auxiliary motor spring and the striking devices; Fig. 4 is an edge view of the same with the bearings in section; Fig. 5 is a sectional side elevation of the striking attachment as applied, the section being on the line 5—5 of Fig. 1, with the cover and 35 dial removed; Fig. 6 is a face view of the auxiliary spring and its barrel with the barrel cover removed; Fig. 7 is a sectional side elevation of the same; Fig. 8 is an enlarged cross section of the clutch mechanism for the driving pinion of the auxiliary motor spring; Fig. 9 is a face view of the locking and releasing device in hour striking position; Fig. 10 is a similar view of the same in half hour striking position; 40 Fig. 11 is a perspective view of the release-

ring and locking pawl; and Fig. 12 is an enlarged under side view of the end of the main lever provided with the spring-pressed arm for engagement with the hour snail.

The striking attachment for the watch is preferably mounted on the front face of the frame A carrying the watch movement, the striking attachment being located directly under the dial B on which indicate the hour and minute hands B' and B². On the hour hand arbor B³ is secured an hour snail C engaged by one end D' of the main lever D fulcrumed at D² on the frame A and pressed on by a spring E. The end D' is preferably in the form of an arm fulcrumed on the main lever D and pressed on by a spring D³ to allow turning of the hour arbor in either a forward or backward direction when setting the watch to correct time without danger of injuring the arm D' by the snail C. The other end of the main lever D is provided with a rack D⁴ having ratchet teeth and an offset shoulder D⁵ adjacent the innermost tooth of the rack D⁴ as plainly indicated in Figs. 1, 2, 9 and 10. The rack D⁴ and the shoulder D⁵ are adapted to be engaged by a locking and releasing pawl F fulcrumed at F' on a bridge A' attached to the frame A of the watch. The locking and releasing pawl F is provided with an arm F² terminating in an angular lug F³ (see Figs. 5 and 11) adapted to engage a stop pin G attached to a gear wheel G' secured on a shaft G² journaled in suitable bearings on the frame A and the bridge A' (see Fig. 5). On the shaft G² is secured a single tooth wheel H adapted to engage the teeth of the rack D⁴ to impart a step by step swinging motion to the same and the main lever D, according to the number of hours to be struck, as hereinafter more fully explained, it being understood that the position of the lever D is governed by the end D' on the snail C. A spring F⁴ presses the pawl F so as to hold the lug F³ normally in the path of the pin G to hold the gear wheel G' and consequently the wheel H from rotating. The shaft G² and the wheels G' and H are adapted to be driven from an auxiliary spring motor I wound up from the main watch spring J of the watch during the time that the main watch spring J is running down, as hereinafter more fully explained. For the purpose men-

tioned the shaft G^2 is provided with a pinion G^3 (see Figs. 3, 4 and 5) in mesh with a gear wheel G^4 secured on a shaft G^5 journaled on the frame A and provided with a pinion G^6 in mesh with a gear wheel I' attached to or formed on the barrel I^2 of the auxiliary spring motor I. The barrel I^2 is mounted to rotate on a shaft I^3 journaled on the frame A and the bridge A', and on the said shaft I^3 is secured the inner end of a helical spring I^4 connected at its outer end to the barrel I^2 (see Figs. 6 and 7). A spring-pressed dog I^5 engages the gear wheel I' to hold the barrel I^2 from rotating in the wrong direction during the winding of the spring.

The spring barrel I^2 is provided with a toothed striker wheel K adapted to engage a click K' fulcrumed at K^2 on the frame A and engaging a shoulder K^3 on the fulcrum end of a striker K^4 fulcrumed at K^5 on the frame A. The hammer K^6 of the striker K^4 is adapted to strike a ring K^7 held suspended on the frame A to sound hours and half hours, as hereinafter more fully explained. The heel of the striker arm K^4 is pressed on by a spring K^8 so that when the click K' is actuated from the striker wheel K the striker arm K^4 is released to allow the spring K^8 to swing the striker inward so that the hammer K^6 strikes the ring K^7 and sounds the same. It is understood that when the locking and releasing pawl F is swung from its normal position to the left then the lug F^3 moves out of engagement with the stop pin G to allow the spring I^4 to rotate the barrel I^2 in the direction of the arrow a' so that the striker wheel K actuates the click K' to release the striker K^4 so that the hammer K^6 strikes the ring K^7 and sounds the same. It is understood that the click K' imparts a return movement to the striker K^4 while the spring K^8 imparts a striking motion to the striker K^4 to sound the ring K^7 whenever the click K' is actuated by the striker wheel K, as before explained.

It will be noticed that when the pin G is released by the lug F^3 , as mentioned, then the gear wheel I' in rotating in the direction of the arrow a' rotates the pinion G^6 of the train of gear wheels G^4 , G^3 and G' to rotate the toothed wheel H and cause the latter to impart a step by step swinging motion to the main lever D by engaging the rack D^4 .

In order to turn the barrel I^2 from the main watch spring J for winding up the spring I^4 , the following arrangement is made: On the shaft I^3 is secured a gear wheel L in mesh with a gear wheel L' fastened on a shaft L^2 journaled in suitable bearings in the frame A and the yoke A'. The gear wheel L' is provided with a spring L^3 adapted to engage a pin L^4 held on the pinion L^5 , mounted to rotate loosely on the shaft L^2 previously mentioned. The pinion

L^5 is in mesh with a minute wheel N driven in the usual manner from the main watch spring J and in mesh with the cannon pinion N' on the arbor B^4 for the minute hand B^2 . The cannon pinion N' has the same number of teeth as the pinion L^5 so that the shaft L^2 is rotated in unison with the arbor B^3 .

On the upper end of the shaft L^2 is secured a cam O having a long hour lug O' and a short half hour lug O^2 diametrically opposite the long hour lug O' , as plainly indicated in Figs. 1, 2, 9 and 10. The lugs O' and O^2 are adapted to engage the free end of a releasing lever P fulcrumed at P' and pressed on by a spring P^2 so as to normally hold the free end of the lever P in the path of the lugs O' and O^2 . The lever P is adapted to engage the releasing arm F^2 on the pawl F so as to swing the said pawl F and the arm F^2 to the left with a view to move the lug F^3 out of the path of the pin G for releasing the striking device, as previously explained. On the under side of the releasing lever P is arranged a depending pin P^3 adjacent the lug F^3 to engage the stop pin G immediately after the lug F^3 has moved to the left out of engagement with the stop pin G. By this arrangement the stop pin G is held temporarily locked by the pin P^3 until the long or the short lug O' or O^2 has passed the free end of the releasing lever P. When this takes place the lever P is swung back to the right by the action of the spring P^2 to release the pin G and allow the gear wheel G' to rotate.

The operation is as follows: When the several parts of the striking attachment are in normal dormant position then the lug F^2 is in the path of the pin G and consequently the striking attachment is held in inactive position with the pawl F in engagement with the shoulder D^5 of the main lever D. During the time the watch is running the auxiliary motor spring I^4 is wound up and the cam O is rotating, and when the minute hand B^2 reaches a twenty minutes past the hour position, the short half hour lug O^2 has engaged and imparted a swinging motion to the releasing lever P so as to swing the pawl F to the left, as previously explained, with a view to disengage the lug F^3 from the pin G and to move the pin P^3 into engagement with the said pin G. At the same time the pawl F disengages the shoulder D^5 to allow the main lever D to swing downward until the first tooth of the rack D^4 engages the free end of the pawl F to hold the latter against further downward swinging movement. When the minute hand B^2 reaches the half hour position and the lug O^2 finally passes the free end of the releasing lever P then the latter swings to the right by the action of its spring P^2 to

release the pin G and to allow the auxiliary motor spring I⁴ to unwind whereby a rotary motion is given to the striking wheel K and to the train of gear wheels G⁶, G⁴, G³ and G'. The striking wheel K now actuates the click K' whereby the striker K⁴ is swung inward and when the corresponding tooth of the striker wheel K has passed the click K' then the spring K⁸ returns the striker K⁴ to cause the hammer K⁶ to sound the ring K⁷. The rotary motion given to the gear wheel G' causes the rotation of the single tooth wheel H which now engages the rack D⁴ and imparts an upward swinging motion to the main lever D so that the free end of the pawl F drops back into reengagement with the shoulder D⁵ owing to the action of the spring F⁴. When this takes place the arm F² has swung to the right a sufficient distance to move its lug F³ into the path of the pin G whereby the wheel G' is stopped after having made one complete revolution.

When the minute hand B² reaches a ten minutes to the full hour position, the hour lug O' has engaged and swung the releasing lever P to the left a sufficient distance to swing the pawl F in a like direction until its free end clears the shoulder D⁵ of the rack D⁴ and allows the main lever D to swing downward until the first rack teeth abuts against the free end of the pawl F. During the movement of the pawl F to the left the lug F³ moves out of engagement with the pin G and the pin P³ moves into engagement with the said pin G to hold the latter in locked position until the lug O' has fully cleared the free end of the lever P, as hereinafter more fully explained. When the minute hand B² reaches a five minutes to the hour position the lug O' has swung the lever P a farther distance to the left to cause the pawl F to disengage the first tooth of the rack D⁴ to allow the main lever D to swing downward by the action of its spring E until the arm D' abuts against the snail C at a point corresponding to the next full hour. If the next full hour is say nine o'clock the lever D swings down the distance of nine teeth of the rack D⁴. When the minute hand B² reaches the full hour position the long lug O² clears the free end of the lever P, and in doing so allows the lever P to swing to the right by the action of its spring P² to unlock the pin G and to allow the wheel G' to rotate, the said wheel G' as well as the striker wheel K being now driven from the auxiliary spring motor I as before explained. The striker wheel K now actuates the click K' which in turn actuates the striker K⁴ to cause the hammer K⁶ to strike the ring K⁷ nine times to indicate the corresponding hour, and at the same time the single tooth wheel H imparts a step by step movement to the rack D⁴ to swing the lever D upward until

the free end of the pawl F drops back into engagement with the shoulder D⁵. When this takes place the lug F³ has returned into the path of the pin G to arrest the movement thereof and thus stop further action of the auxiliary motor spring I for the time being.

It is understood that when the main lever D is swung upward by the action of the rotating single tooth wheel H engaging the rack D⁴, the free end of the pawl F drops successively into the corresponding teeth of the rack D⁴ thus holding the lug F³ out of the path of the pin G and allowing the wheel G' to rotate until the free end of the pawl F reengages the shoulder D⁵. It is also understood that when the single tooth wheel H lifts the rack D⁴ an upward swinging motion is given to the lever D to lift the arm D' out of engagement with the snail C. The above-described operation is repeated for each half hour and full hour, that is, when the minute hand B² nears the half hour position the lug C² imparts a swinging motion to the lever P, and when the minute hand B² nears the full hour the lug O' engages the said lever P and actuates the same.

The striking attachment shown and described can be readily applied to watches as now constructed with a few minor changes in the form of the frame or plate A.

Having thus described my invention, I claim as new and desire to secure by Letters Patent:

1. A time piece provided with a movement frame, and a striking attachment comprising striking devices, a spring for actuating the striking devices, a gear wheel driven from said spring and provided with a stop pin, a single tooth wheel rotating with said gear wheel, a locking and releasing device having spaced arms, one of which is adapted to engage the said stop pin, the other arm forming a pawl, a main lever provided at one end with a rack adapted to be engaged by the said pawl and by the said single tooth wheel, an hour snail adapted to be engaged by the other end of said main lever, and means for periodically moving the said locking and releasing device into release position, the said locking and releasing device, the releasing means, the main lever and its rack, and the hour snail being arranged on the front face of the movement frame and in substantially the same plane.

2. In a striking attachment for time pieces, the combination with the movement frame, and striking devices, of the spring for actuating the striking devices, a train of gear wheels driven from the spring, one of said gear wheels being provided with a stop pin, a single tooth wheel on the shaft of said gear wheel, a main lever provided with a rack, adapted to be engaged by the single tooth wheel, an hour snail adapted to be engaged by said lever, a locking and re-

leasing device having a member adapted to engage the said stop pin, and a pawl member adapted to engage the said rack, and a releasing lever for periodically moving the locking and releasing device to release position, the said releasing lever engaging the stop pin, when the locking and releasing device is released, to temporarily lock the gear wheels, the said main lever and its rack, 10 the hour snail, the locking and releasing device and the releasing lever being arranged on the front face of the movement frame and in substantially the same plane.

3. A time piece provided with a movement frame, and a striking attachment comprising striking devices, a spring for actuating the striking devices, a train of gear wheels driven from the spring, one of said gear wheels being provided with a stop pin, 15 a single tooth wheel on the shaft of said gear wheel, a pivoted and spring-pressed locking and releasing device having spaced arms between which the said single tooth wheel extends, one of said arms terminating in an angular lug adapted to engage the 20

25

said stop pin, the other arm forming a pawl at its free end, a main lever provided at one end with a rack adapted to be engaged by the pawl of said locking and releasing device and by the said single tooth wheel, 30 an hour snail, adapted to be engaged by the other end of the said main lever, a driven cam, and a releasing lever controlled by the said cam and adapted to engage the said angular lug on the arm of the locking and 35 releasing device to move the latter periodically into release position, the said locking and releasing device, the releasing lever, the main lever and its rack, and the hour snail being arranged on the front face of the 40 movement frame and in substantially the same plane.

In testimony whereof I have signed my name to this specification in the presence of two subscribing witnesses.

OLAF E. GISET.
